CARTRIDGE FOR EXPLOSIVES

Milton F. Lindsley, Jr., Kings Mills, Ohio, assignor
to The King Powder Company, Kings Mills,
Ohio, a corporation of Ohio

Application May 24, 1939, Serial No. 275,498

3 Claims. (Cl. 102—4)

This invention relates to cartridges for explosive compositions. The cartridges are intended to be loaded with explosive and then lowered into deep oil or gas wells. Detonation of the explosive in the cartridge serves to relieve the congestion of the strata containing the oil or gas, and the explosion starts or increases the flow from the well.

In most cases, the wells are from four to eight inches in diameter; the depth varies from several hundred to several thousand feet or more. Usually, the cartridges are lowered into the well until the requisite charge has been placed in position. Detonation is caused either by dropping a very sensitive high-explosive Jack-squib down the well on the top column of explosive, or by equipping the uppermost cartridge of the column with an electrically detonatable blasting cap.

Up to the present time, well cartridges have been made of sheet metal and these have been loaded with powder at the well, or in the field. These operations are dangerous and time consuming, while the cartridges themselves are cumbersome and expensive.

An objective of this invention has been to provide cheap cartridges suitable for the purpose, but adapted particularly to be loaded at the powder plant and shipped to the well ready for usage.

A further objective has been to provide unitary cartridges arranged to be strung together, in chain fashion, to constitute a column of explosive suitable to be lowered intact into the well.

It has been another objective to provide a cartridge comprised primarily of a paper container, yet sufficiently strong to withstand the tensional strain of the weight of the chain of loaded cartridges below it when it is being lowered into a well, and sufficiently strong to withstand the compressional weight of a column of loaded cartridges above it when it is at the bottom of the well. These and other objectives are disclosed in the following specification and in the accompanying drawing which illustrates a preferred embodiment of the invention.

In the drawing:

Figure 1 is a perspective view of a cartridge of the invention. This view also illustrates the manner in which several cartridges are linked together.

Figure 2 is a cross-sectional view taken longitudinally of the cartridge.

Figure 3 is a top plan view.

Figure 4 is a view looking upwardly at the bottom of the cartridge.

Briefly, it is the concept of the present invention to combine a paperboard explosive container which is relatively strong compressively, with a lightweight cage made of steel straps which is relatively strong tensionally. The pa-

perboard container carrying the explosive is carried within the cage, with the steel straps resting adjacent the walls of the container. Spiders are provided at each end of the cage adjacent the ends of the container, for keeping the straps of the cage in their predetermined positions.

Connecting rings or snap hooks are provided at each end of each cage, so that the cartridges can be strung or linked together in chain form when a number of them are to be lowered simultaneously into a well. During the lowering operation, the weight of the column is carried through the connecting strap elements of the cages, so that there is no danger that the cartridges of the chain will break or separate. The strength of the paperboard containers is sufficiently great that they will not crush under the weight load when the column is at the bottom of the well. The structure therefore provides cartridges which are very cheap to construct, and yet cartridges which are lighter in weight and much safer to handle and use than the cartridges which have been available in the past.

25 In the drawing, the paperboard container is indicated generally at 1. This unit preferably is comprised of a paperboard tube having a lid 2 and a cap 3; the tube preferably being spirally wound in the conventional manner. The lid 2 preferably is made of paper or the like and fits over the tube. This lid is arranged for removal when the tube is being loaded with explosive, and, after the loading, the lid is sealed in position either by means of a suitable adhesive or by means of a gummed tape wrapper 4.

The cap 3 preferably is made of sheet metal in the form of a truncated cone having a bottom plate 5. The conical form of the cap is employed so that it will serve to guide the cartridge as it is being lowered down the bore hole of a well. In the preferred structure, the conical wall 6 of the cap and the bottom plate 5 are joined together at a peripheral seam; this seam preferably extends below the surface of the plate so as to provide an annular flange 7. A paperboard member 5a extends over the bottom plate 5 and serves to close the bottom of the cartridge. The central portion of this member is offset inwardly as at 1a to permit the ring, which is subsequently described, to clear it.

50 Referring to Figures 2 and 4, the plate 5 of the bottom cap contains a central aperture 8 and a plurality of slot-like apertures 9 which are spaced annularly inwardly of the flange 7. Strap elements 10 and 11 are threaded through the slots 9 and, therefore, the pairs of straps form a basket for the cap 3 constituting the bottom of the paper container. The straps 10 and 11 may be threaded through diametrically opposed slots, to overlap, as shown in the drawing, or

they may be threaded through adjacent slots, which are angulated in position to receive the straps without distorting them, or in other suitable manner.

The straps 10 and 11 preferably extend upwardly adjacent the interior surface of the cap 3, as shown in Figure 2, but exteriorly of the paper container. At the upper end of cartridge, the straps are threaded through slots 12 which are spaced annularly in a spider member 13. This spider also contains a central aperture 14 and has an upstanding marginal flange 15. The diameter of the cap inwardly of the flange 15 complements the diameter of the depending flange 7 of the cap 3, so that the caps of adjacent cartridges can be nested together, if desired. The straps 10 and 11 can be threaded through opposed slots in the upper spider 13 or may be threaded through adjacent slots appropriately angulated. It is preferable that the straps be parallel to one another and to the longitudinal axis of the cylinder for even distribution of the load to which they are subjected during the period when the cartridges are being loaded in position.

A band 16 of adhesive tape or other suitable material is wrapped over the straps around the paperboard container, so as to keep the straps located in their predetermined position.

In the preferred structure, the strap elements 10 and 11 comprise lengths of strap metal appropriately clamped or clasped together as at 18, so that they form loops which respectively embrace the sides and ends of the container, and which collectively constitute a cage for the container. One type of clamp suitable for this purpose is known as the "Acme Steel Strap"; the details of such a clasp are shown particularly in Patent No. 1,260,016 of March 19, 1918.

As shown in the drawing, the strap elements are divided into upper and lower mating portions of loops; the lower portions extend from points approximately midway of the cartridges, down through the lower spider slots of the cap 3, and up to approximately midway of the cartridge on the other side; these strap portions are connected by means of the clasps 18 to complementary strap portions depending from the upper spider. Thus, the one form of cage disclosed is comprised of a pair of loops arranged at 90° from one another radially, each loop being made up of an upper portion and a lower portion joined together. The upper and lower strap portions are threaded easily and quickly through the slots in the spiders and production of the cartridges in quantities is simplified. If desired, the strap can be employed to interconnect the caps alone, if modification of the structure is requisite or desired for constructing cartridges for particular purposes. A typical steel strap stretcher may be employed for bringing the straps into position, after which the straps may be joined as by crimping, or other suitable fastening means.

For the purpose of interconnecting a plurality of the cartridges in the form of a chain, the rings 19 and 20 are carried by the straps from the lower and upper ends of the cartridge respectively, with the respective apertures 8 providing clearance for them. Each of these rings carries a snap hook or connector link 21. By joining these snap hooks together, as shown in Figure 1, the cartridges readily are interconnected to form a chain.

By virtue of the stackability of these cartridges due to the formation of the ends of them, a continuous column of powder readily may be installed in a well. The unit cartridges constituting this column do not tend to "settle" or telescope with one another as in the case of metal cartridges having pointed ends.

Having described my invention, I claim:

1. A deep well cartridge for explosives, comprising a paperboard tube, strap members for supporting the tube, a truncated conical cap of sheet metal telescopically engaging the tube at one end, the said strap members being arranged in the form of loops which are spaced apart and which extend around the end of the tube with which the said cap is associated, the said cap having apertures therein, with the strap members being threaded through the cap apertures so as to pass over the outside of the cap end and pass under the side walls of the cap along the tube, whereby the cap holds the straps in spaced relationship, the said strap members extending along the tube and over the other end thereof with the ends of the respective straps being interconnected to form continuous loops longitudinally around the tube, the said continuous loops cooperating to provide a basket by which the tube may be supported therefrom.

2. A deep well cartridge for explosives, comprising a paperboard tube, strap members which are spaced apart from one another and which extend longitudinally around the tube, a truncated conical cap of sheet metal telescopically engaging the tube at one end, the said straps being arranged in the form of loops and the said truncated cap having apertures in its end wall, with the straps being threaded through the cap apertures so that the ends of the loops pass over the outside of the cap end and the portions of the straps adjacent the loop ends pass under the side walls of the cap and along the tube, whereby the cap holds the straps in spaced relationship, another cap member extending over the end of the tube at the end opposite the truncated cone and having strap receiving perforations, with the said straps passing along the wall of said tube and being threaded through said perforations to cross over said second cap exteriorly thereof, the strap means being connected to form continuous loops providing a basket through which the tube may be supported.

3. A deep well cartridge for explosives, comprising a paperboard tube, strap members forming loops which are spaced apart from one another radially of the tube, a truncated conical cap of sheet metal telescopically arranged around the tube at one end, the said cap having apertures therein with the straps being threaded through the cap apertures so as to cross one another at the outside of the cap end and pass under the side walls of the cap end along the tube, whereby the cap holds the straps in spaced relationship, the said straps passing along the tube and passing over the opposite end thereof and the ends of the straps being interconnected to form continuous loops providing a basket by which the tube may be supported, and wrapper means extending around the tube over the straps intermediate the ends of the tube.
